DESIGN FOR A TOURING CAR BODY

Charles S. Ash, Birmingham, Mich.

Application July 7, 1933. Serial No. 48,652

Term of patent 14 years

To all whom it may concern:

Be it known that I, CHARLES S. ASH, a citizen of the United States, residing at Birmingham, in the county of Oakland and State of Michigan, have invented a new, original, and ornamental Design for Touring Car Bodies, of which the following is a specification, reference being had to the accompanying drawing, forming part thereof.

Figure 1 is a side elevation of a touring car body;

Fig. 2 is a top plan view thereof;

Fig. 3 is a front end elevation;

Fig. 4 a rear end elevation; and

Fig. 5 is a perspective view showing the rear end and side of the body, disclosing my new design.

I claim:

The ornamental design for a touring car body, as shown.

CHARLES S. ASH.
